UNITED STATES PATENT OFFICE.

OLIVER B. SHALLENBERGER, OF ROCHESTER, ASSIGNOR TO THE WESTINGHOUSE ELECTRIC COMPANY, OF PITTSBURG, PENNSYLVANIA.

DESIGN FOR A BOX FOR ELECTRIC METERS.

SPECIFICATION forming part of Design No. 19,723, dated March 25, 1890.

Application filed January 21, 1890. Serial No. 337,656. Term of patent 14 years.

To all whom it may concern:

Be it known that I, OLIVER B. SHALLENBERGER, a citizen of the United States, residing at Rochester, in the county of Beaver and State of Pennsylvania, have invented and produced a new and original Design for Cases or Boxes for Electric Meters, of which the following is a specification, reference being had to the accompanying drawings, forming part thereof—

Figure 1 is a front view of the meter-box, and Fig. 2 is a side view thereof.

The leading feature of the design is the projecting lower portion of the front in connection with the receding upper portion provided with the opening or window.

$A'A^2$ represent the side walls, and B the front of the case or box. The lower portion of the front is rounded or curved, as shown

at b . This portion is joined with the upper flat portion b^2 by a horizontal or slanting wall b^3 . The upper portion b^2 extends straight across between the side walls $A'A^2$, and an opening or window C is constructed through it. The opening is suitably configured and ornamental. c indicates another opening.

The top of the case is closed by a wall A^3 , which is of rectangular shape.

What I claim is—

The design for a meter-box, as herein shown and described.

In testimony whereof I have hereunto subscribed my name this 14th day of January, A. D. 1890.

OLIVER B. SHALLENBERGER.
